UNITED STATES PATENT OFFICE

2,030,698

IMMERSION TUBE TYPE FURNACE

George J. Hales, Rocky River, Ohio, assignor to
General Electric Company, a corporation of
New York

Application April 12, 1934, Serial No. 728,194

4 Claims. (Cl. 286—3)

This invention relates to furnaces, more particularly to electric furnaces for carrying out certain heat treating operations for metals, such as annealing and the like, and it has for its object the provision of an improved furnace of this character which is more efficient in its operation and which is more durable than those heretofore known.

This invention has particular application to furnaces for treating wire, rods, tubes and like forms of metals, such as ribbon, sheets, etc., wherein the furnace charge, that is, the material to be treated, is supplied to and passed through the furnace. Certain furnaces of this type heretofore known comprise a relatively elongated tube, constituting a treating chamber, in which a suitable selected atmosphere, such as hydrogen, is maintained. This tube is provided with a heating zone wherein the material is heated to the treating temperature and a cooling zone wherein the material is cooled before it is withdrawn from the furnace. The heating zone is usually heated by means of electric heating elements arranged on the exterior of the tube in a heating chamber that surrounds or envelops the heating zone.

These furnaces have, in the main, been quite satisfactory, but are subject to certain disadvantages. The heat distribution in the heating portion of the tube is not always uniform and consequently the temperature throughout this zone may vary. It may happen, therefore, that the metal being treated will not be heated uniformly as it passes through the furnace. Moreover, it has been found that an uneven distribution of the heat in the tube at the heating zone tends to warp the tube out of shape.

This invention contemplates the provision of improved means for heating the furnace, whereby heat is uniformly distributed over the heating zone so as to insure a uniform temperature condition throughout the zone. This assures a uniformly heated product, and moreover, prevents warping of the tube due to uneven heating.

In addition to this, this invention contemplates the provision of a furnace which is much quicker in its operation than those heretofore generally known, whereby the output of treated metal is materially increased.

In accordance with this invention, the heating zone of the furnace is heated by a mass of heated material, preferably in the liquid state, which has a high heat storage capacity and a relatively high thermal conductivity. This mass

of material is arranged to completely cover all of the exterior surface of the walls of the tubular chamber constituting the heating zone so as to apply the same quantity of heat to all portions of the zone throughout its length. The tubular heating zone is thus uniformly heated to the same temperature throughout so that the successive lengths of material being treated will be uniformly heated as they pass through the heating zone.

The heating medium may be of any suitable material having a relatively high heat conductivity and thermal capacity, such as lead, aluminum, copper, mercury, etc. The heating medium may be heated conveniently in a suitable metal melting tank or crucible in which the heating zone of the treating tube is located.

For a more complete understanding of this invention, reference should be had to the accompanying drawing in which Fig. 1, is a fragmentary vertical sectional view of an electric metal melting furnace arranged in accordance with this invention; Fig. 2 is a fragmentary plan view of the electric furnace shown in Fig. 1, portions being shown in section and portions being broken away so as to illustrate certain details of construction; Fig. 3 is a fragmentary vertical sectional view of an electric furnace of modified form arranged in accordance with my invention; and Fig. 4 is a diagrammatic view illustrating temperature control means used in my furnace.

Referring more particularly to Figs. 1 and 2, I have shown my invention in one form as applied to an electrically heated metal annealing furnace comprising a plurality of metallic tubes 10, each of which forms an elongated treating chamber. The tubes 10 have identically the same construction. Each treating tube 10 comprises a heating zone 11 and a cooling zone 12. The cooling zone 12 is surrounded by a jacket 13 through which a cooling fluid, such as water, may be circulated by means of an inlet pipe 14 and an outlet pipe 15. This jacket, as shown, functions to cool all of the tubes 10.

The heating zone 11 of each tube 10 is heated uniformly throughout its entire length by means of a mass 16 of a suitable heat transfer medium completely enveloping the outer surface of the portion 11. As previously pointed out, this heat transfer medium preferably will be formed of a metal having a relatively high thermal capacity and heat conductivity, such as lead, aluminum, copper, mercury, etc.

It is contemplated that this heat transfer

medium 16 will be heated sufficiently to bring it to the liquid state so that all portions of the heating chamber 11 will be completely covered by and in intimate thermal contact with the heat transfer medium, whereby all parts of the heating zone throughout its length will be heated to the same temperature. The transfer medium 16 is heated to the liquid state by a suitable electrically heated device which, as shown in Figs. 1 and 2, is in the form of a crucible or melting chamber through which the heating tubular portion 10 is passed.

This heating device, as shown in Figs. 1 and 2, comprises a metal receptacle or pot 17 for the heat transfer medium 16. The receptacle 17, as shown, is received in and supported by suitable heat insulating walls 18 which cover the side and bottom walls of the receptacle. As shown, the receptacle 17 rests upon the bottom wall of the outer lining 18. This outer lining may be formed of any suitable material, such as suitable heat refractory bricks. The receptacle is provided at its top with a peripheral flange 20 upon which rests a suitable cover 21 made of any suitable heat refractory material.

The metal transfer medium 16 may be heated in any suitable manner, but where relatively low temperatures are required in the heating zone 11, it is preferable to employ immersion heating elements of the sheathed type for this purpose, such as disclosed in the U. S. patent to C. C. Abbott, No. 1,680,718, dated August 14, 1928. As shown a plurality of electrical immersion heaters 22 of this type are supported in the interior of the receptacle 17. Each of the heaters 22 has a suitable resistance element embedded in refractory insulating material and surrounded by a metallic sheath, which is cast in a mass of a suitable metal. The leads 23 of the resistance element are passed through an insulating tube 24 and outlet box 25 and may be connected to any suitable source of electrical supply. It will be understood that any suitable number of these elements may be used. As shown, I have provided eight of the elements, two in each side and end wall of the crucible. Each of the heating elements 22 has an upper horizontal arm 22a which is secured to the refractory lining 18 by means of bolts 22b so as to support the heating element 22 in the receptacle 17. These elements may be, and oftentimes preferably will be secured to the rim or flange of the crucible. Preferably, the walls of the crucible will rise somewhat above the walls 18, as clearly shown in Fig. 1, and preferably, the upper protruding portions of the crucible walls will be provided with notches or cut away portions 26 to receive the arm portions 22a that rest upon the walls 18. By reason of this construction, the cover member 21 can lie flush on the flange 20 at the top of the receptacle.

It will be observed that the heating portion 11 of each tube 10 is supported within the crucible above its bottom wall so that the heat transfer medium 16 can completely envelop the tube.

The tube 10 where it passes out of the crucible, that is, where it joins into the cooling zone 12 has a fluid-tight joint 27 with the wall of the crucible. This joint may be formed by welding, or otherwise substantially integrally uniting the walls of the tube with the metallic walls of the crucible.

A fluid-tight seal is also provided between the crucible and that portion of the tube that enters the crucible so as to provide for thermal expansion of the tube within the crucible. This seal

comprises a tube 28 surrounding the tube 10 on the exterior of the crucible at the entrance end of the heating zone 11 and communicating with the crucible, as clearly shown in Fig. 1. This tubular member has a fluid-tight joint 29 with the adjacent wall of the crucible. This joint also may be formed by welding or otherwise integrally uniting the tubular member with the crucible wall. The outer end of the tube is closed by a suitable cover member 31 which is welded or otherwise secured to the tube with a fluid-tight joint 32. The cover is provided with a centrally arranged aperture through which the tubular member 10 passes. A separate tube 28 may be provided for each tube 10, or a single tube 28 may be provided for all of the tubes 10.

It will be observed in view of the foregoing arrangement that the liquid transfer medium within the crucible can flow into the tube 28 so as to completely surround the portion of the tubular treating chamber 10 on the exterior of the crucible immediately next to the crucible. The tubular member 28 will have a diameter sufficiently large to provide a relatively thick layer of the heat transfer medium about the tubular member 10.

The tube 28 is cooled by means of a suitable cooling medium 33 so that the layer of heat transfer medium surrounding the tubular member 10 will be solidified. As shown, the tube is cooled by means of a suitable cooling jacket 34 through which the cooling fluid 33, which may be water, is circulated by means of an inlet pipe 35 and an outlet pipe 36.

It will be observed that by reason of this arrangement, the frozen or solidified metal forms its own seal. This seal will permit unequal expansion between the tubular treating tube 10 and the crucible and thereby prevent warping of the tube. This is because the tube 10 will move relative to the sealing mass so as to provide for unequal movements of the tube 10 and the crucible walls due to thermal expansion. If desired, the metal surrounding the tube 10 may be covered so as to put partially solidify it.

A suitably selected or controlled medium, such as hydrogen, is maintained in the heating and cooling zones 11 and 12. This medium is supplied to each of the furnace tubes 10 through an inlet pipe 37 which communicates with the tube substantially at the juncture of the heating and cooling zones. The medium entering at this point divides and flows in opposite directions through the heating and cooling zones. Preferably a common supply manifold 38 for the various supply tubes 37 will be provided.

It will be understood that in the operation of the furnace, the material to be treated will be passed through the furnace treating chambers 10—first through the heating zone 11 and then through the cooling zone 12. It will also be understood that the material in passing through the heating zone will be heated to the treating temperature, while maintained in the selected atmosphere in this zone, and will be passed through the cooling zone 12 where it will be cooled substantially to room temperature, while in the selected atmosphere, before the material is passed out from the furnace.

The heating elements 22 are controlled to maintain a constant operating temperature in the bath 16. Any suitable temperature control means may be used for this purpose. In Fig. 4, I have shown in quite diagrammatic form one means for controlling the heating elements 22 to hold a constant temperature in the bath 16.

As shown in this figure, the heating elements 22 are connected in delta arrangement. The elements are connected with a suitable three-phase source of electrical supply 48 through a contactor 41. The contactor 41 is energized from a suitable source of electrical supply 42, and its energization to control the energization of the heating elements 22 is controlled by a relay 43. The relay is energized from the source 42 and its energization is controlled by a suitable temperature responsive element 44 immersed in the metal 16 so as to respond to its temperature, as shown in Figs. 1 and 2. It will be understood that the device 44 will be arranged to control the energization of the relay 43 to energize the contactor 41 to apply the heat when the temperature of the metal 16 falls below a predetermined value, whereas when the temperature of the metal 16 rises above the predetermined value it will operate the relay to deenergize the contactor 41 so as to shut off the heat.

It is to be noted that I have provided means for uniformly heating the heating zone 11 throughout its length. The relatively large mass 16 of heat transfer medium having a relatively large storage capacity provides a large reservoir of heat which is available at all times. And moreover, by reason of the fact that the transfer medium 16 has a relatively high heat conductivity, heat will be transferred from the medium 16 to the heating chamber 11 at a very rapid rate, the rate, of course, depending upon the thermal capacity and the heat conductivity of the particular transfer medium. If lead be used, the transfer is six times or more as rapid as if the tube 11 were heated in the furnaces heretofore generally used. It is possible, therefore, to pass the material being treated through the furnace at a considerably greater speed than has been possible heretofore.

Moreover, not only is the output of my furnace increased, but it has a more uniform quality because all portions of the material passed through the furnace are heated uniformly to the treating temperature in the heating zone.

Another advantage of my furnace is that there is considerably less warpage of the tubular members 10, because they are evenly and uniformly heated throughout the entire length of the heating zone.

If higher temperatures are desired it is preferable to use the arrangement shown in Fig. 3. In this arrangement the heat treating tubes 50 are arranged in substantially the same fashion as are the tubes 10, that is, they are provided with a heating zone 51 and a cooling zone 52. The heating zone is heated by a heat transfer medium 53 which is heated to a liquid state in a suitable crucible 54. The crucible 54 is arranged in substantially the same fashion as the crucible of the furnace of Figs. 1 and 2. The crucible in Fig. 3, however, is not heated by immersion heating elements, but by relatively high temperature resistance heating elements 5. These resistors preferably consist of flat ribbons of a suitable heat resistance material, such as a nickel-chromium alloy, which are hung in a series of loops on suitable supports, such as refractory hangers 56 secured in the side walls of said insulating outer lining 51. Suitable terminals 58 for the heating resistors are brought out through the lining 51. Similar resistors 59 may be positioned beneath the bottom wall of the crucible. The heating means for this furnace likewise will be provided with suitable temperature control means

arranged so that a constant temperature is held in the bath 53.

The remainder of the construction of the furnace of this form is identically the same as the form shown in Figs. 1 and 2, and the furnace 5 operates in substantially the same fashion.

It is preferable to heat the transfer medium to the liquid state. It will be understood, however, that the medium, after it has once been heated and allowed to cool to the solid state, may 10 then subsequently be used in the solid condition to transfer heat to the tube 10. The liquid state, however, is more desirable.

While I have shown particular embodiments of my invention, it will be understood, of course, 15 that I do not wish to be limited thereto since many modifications may be made, and I, therefore, contemplate by the appended claims to cover any such modifications as fall within the true spirit and scope of my invention.

What I claim as new and desire to secure by Letters Patent of the United States, is:

1. A continuous process annealing furnace wherein the material being annealed is passed through the furnace comprising a crucible, an 25 elongated metallic tubular metal member forming a treating chamber having a portion constituting a heating zone passing through said crucible above its bottom wall, a heat transfer medium having a relatively high heat conductivity and thermal capacity within said crucible, means for applying heat to said medium to liquefy it whereby it envelops said heating zone to uniformly heat it throughout its length, means providing a fluid impervious joint between said tube 35 at one end of the heating zone and the wall of said crucible where said tube passes out of said crucible, and means for cooling a portion of the heat transfer medium at the other end of said heating zone to solidify said medium and thereby seal said tube at said outer end of said zone.

2. A metal treating furnace comprising a crucible, an elongated metallic tubular member forming a treating chamber having a portion constituting a heating zone within said crucible 45 above its bottom wall passing through the opposite walls of said crucible, a metallic heat transfer medium having a relatively high heat capacity and thermal conductivity within said crucible, means for applying heat to said transfer medium 50 to liquefy it whereby it envelops the portion of said tube forming said heating zone to uniformly heat it throughout its length, a fluid-tight joint between said tubular member at the exit end of said heating zone and said crucible where said 55 tubular member leaves said crucible, a tubular member communicating with said crucible at the entrance end of said heating zone and surrounding a portion of the length of said tubular member on the exterior of said crucible so that said portion is surrounded by a layer of said heat transfer medium, and means for bringing a cooling medium into thermal relation with said tubular member so as to solidify said layer of transfer medium.

3. A continuous process furnace comprising a crucible containing a heat transfer medium, means for heating said medium to liquefy the same, a treating tube extending through said crucible and immersed in said medium, means forming a joint impervious to said medium between one side of said crucible and said tube and a joint between another side of said crucible and said tube comprising a cooled and solidified portion of said medium.

4. A continuous process furnace comprising a crucible containing a normally solid heat transfer medium, means for heating said medium to liquefy the same, a treating tube extending through said crucible and immersed in said medium, and means forming a joint impervious to
- 5

said medium between one side of said crucible and said tube, said crucible having an outward extension at the opposite side thereof through which said tube passes and a part of the medium in said extension being in the solid form.

GEORGE J. HALES.
